UNITED STATES PATENT OFFICE

JOHN ALBERT CHEAPE, OF CHARLOTTESVILLE, VIRGINIA

LIFTING JACK

Application filed October 6, 1927. Serial No. 224,448.

My invention relates to an improvement in lifting jacks.

The primary object of this invention is to provide a quick-acting jack, one that will respond instantly to pressure upon the part to be lifted, or to which the jack is to be applied, by causing the base or lower portion of the jack to drop to the floor or ground, so that it is ready to lift the moment the rod is turned, if a rod is employed, or the lever is raised and lowered if it is of the lever type of lifting jack.

The invention consists of two slidably connected members temporarily locked with a trip which latter becomes released upon being pressed against the part to which the lifting power is to be applied, with the result that the base of the jack drops to the floor or ground below, instantly making the jack ready for the lifting operation.

In the accompanying drawings:

Fig. 1 is a perspective view showing the jack in its collapsed position just as it is about to be pressed under an axle from beneath;

Fig. 2 shows the position it instantly assumes on being slightly pressed up against the axle;

Fig. 3 is a section through the jack as shown in Fig. 2;

Fig. 4 is an enlarged sectional detail showing the top of the jack in section and the trip in elevation;

Fig. 5 is a view showing an application of my invention to the ordinary type of lever jack; and

Fig. 6 shows the various parts of this jack disassembled.

In the construction shown in Figs. 1 to 4, A represents the base of the jack; and 1 is a hollow post rising from its center and having a slot 2 in one side. The numeral 3 represents an inner tube fitted to and telescopically connected with the hollow post 1, and this tube has a row of ratchet-teeth 4 protruding through the slot 2, and a gravity pawl 5 with a weighted handle 6 is held normally in contact with these ratchet teeth as shown in Figs. 1, 2 and 3.

The numeral 7 is a screw, the threads of

which have a comparatively slight pitch, as shown in Fig. 3, and this screw is fitted to move up and down in the tube 3 as is the hollow post 1 to slide upon the tube 3. A head 8 is mounted upon the upper end of the screw 7, as viewed in Fig. 4, to receive and sustain the weight of the object to be lifted, as illustrated in Figs. 1 and 2.

A bevel gear 9 is provided with internal screw-threads 10 which register with the threads of the screw 7, and the gear 9 rests and turns upon the upper end of the tube 3 as illustrated in Fig. 3, and this gear 9 is turned by a driving-gear 11, supported by the tube 3 which gear 11 is turned by the rod 12, which is the means employed by the operator to raise the load by turning the gear 9 around the screw 7, which causes the latter to raise or lower according to the way the actuating-rod 12 is turned.

A trip 13 is pivoted at 14 at one side of the head in position to retire into the recess 15 formed thereover, as shown in Fig. 4 when upward pressure is applied to the axle or other object to be lifted upon the trip. The trip is provided with a catch 16 at its lower end, which is adapted to engage the shoulder 17 on the bracket 18 which supports the pawl 5, and a spring 19 holds the trip in its normally raised position as will be seen by referring to Fig. 4.

Assuming the jack to be in its normally closed or collapsed state, as shown in Fig. 1, that is to say with the telescopic members all locked together by the engagement of the latch 16 beneath the shoulder 17 on the bracket 18, all the operator has to do is to hold his hands on the rod 12 and raise the jack up against the axle or object to be lifted or jacked, with the trip beneath and against the object, with just a slight upward pressure, that is enough to overcome the tension of the spiral spring 19 with the result that the trip is pressed down into the recess 15, as shown at Fig. 2, causing the catch 16 to pull away from the shoulder 17, as shown in Fig. 2. This release causes the instantaneous drop of the base to the ground, the pawl 5 riding over the teeth 4 and then locking into the

tooth which comes opposite, as shown in Fig. 3.

This leaves nothing for the operator to do but to turn the rod and raise the object to be lifted; in other words, with the saving of all the time that is usually consumed in screwing or lifting a jack from its lowered position up to the object to be lifted before beginning to lift. With this device, the mere touching of the jack with the thing to be lifted is the only brief preliminary to the actual lifting of the article.

To lower the load, the rod 12 is turned in the reverse direction until the load is supported on the ground or floor, and then by raising the handle 6 until the pawl 5 is removed from the teeth, it permits the upper part of the jack, including the tube 3, the screw, the head, and the trip, to drop back into the collapsed position shown in Fig. 1, by gravity, due to the weight of said part.

In Figs. 5 and 6, I have merely sought to illustrate the same invention as applied to the ordinary type of lever-jack. I employ the same trip 13^a pivoted to the bar 20, the catch 16^a and the lug 17^a. The head is on the usual toothed bar 20 in this instance, and this is operated in the usual manner by the hand lever 21, the action upon the bar being made reversible as usual by the trigger 22.

The frame 23 in this form of device is telescopically mounted in a hollow post 24 mounted on a base 25 and said frame 23 is provided with a set of ratchet-teeth 26, in which the pawl 27 engages, and the latter is controlled by the weighted lever 28. This jack is applied in the same manner as the jack illustrated in Figs. 1 to 4. The operator lifts it by means of the hand-lever, pressing some portion of the front 13^d of the trip 13^a or the horn 13^c against the surface of the object to be lifted. This causes the hook 16^a to become disengaged from the lug 17^a with the resultant drop of the base 25 and the frame 24 to the ground, whereupon the pawl 27 engages a tooth lower down on the ratchet-teeth 26, and the operator now proceeds to raise it and lower the lever to lift the bar 20 in the usual fashion of this type of jack.

In other words, I consider that the real novelty and advantage in my invention over the prior art resides in the time-saving element, due to the instantaneous dropping of the base of the jack through the space intervening from the object to be lifted to the ground or floor, in that way eliminating the usual lost motion of first adjusting the jack to this space by the screw or lever method as a preliminary step to the application of lifting power.

Obviously the results may be obtained by a backward pull or push upon some part of the trip.

I claim:

1. A lifting-jack including slidably con-

nected members, a trip connected with one of said members, and having a catch in position to engage the other member, whereby to hold the members in closed adjustment, a portion of said trip located in position to engage the object to be lifted, thereby causing the release of the catch from the other member and permitting it to drop by gravity to the ground or floor.

2. A lifting-jack including telescopic members, a trip connected with one of said members, and having a catch in position to engage the other member, whereby to hold the members in closed adjustment, a portion of said trip located in position to engage the object to be lifted, thereby causing the release of the catch from the other member and permitting it to drop by gravity to the ground or floor, and means for automatically locking the members in the extended relation.

3. A lifting-jack including telescopic members, a trip connected with one of said members, and having a catch in position to engage the other member, whereby to hold the members in closed adjustment, a portion of said trip located in position to engage the object to be lifted, thereby causing the release of the catch from the other member and permitting it to drop by gravity to the ground or floor, means for automatically locking the members in the extended relation, and independent means for raising one of the members.

4. A lifting-jack including telescopic members, independent means for locking the members in closed and in extended adjustment, one of said locking means located in position to engage the object to be lifted, whereby to unlock the members and permit the lower one to drop to the ground or floor, the other lock acting automatically to hold the members in this extended position, and manual means for lengthening the jack to apply lifting power to the object to be raised.

5. A lifting-jack including two telescopic members slidably connected, a head, means for raising and lowering said head, a trip having means for automatically locking the two members when in closed position, said trip extending into the head and projecting thereabove in position to engage the object to be lifted in advance of the head, whereby to cause a release of the locked members and permit the lower member to drop to the ground or floor.

6. A lifting-jack including two telescopic members slidably connected, a head, means for raising and lowering said head, a trip having means for automatically locking the two members when in closed position, said trip extending into the head and projecting thereabove in position to engage the object to be lifted in advance of the head, whereby to cause a release of the locked members and permit the lower member to drop to the

ground or floor, and a gravity pawl for automatically locking the telescopic members in their extended position.

7. A portable lifting-jack including slidably connected members, a trigger for holding said members together, said trigger adapted to be released by pressure against the object to be lifted, whereby the lower member is permitted to drop instantaneously to the ground or floor by gravity.

8. A lifting jack including members longitudinally movable relative to each other, and means normally holding said members against extending action, said means being released by engagement with the object to be lifted.

9. A lifting jack including members slidably mounted relative to each other, and means normally holding said members against extending action, said means being released by engagement with the object to be lifted to permit the jack to be extended between the object to be lifted and the floor or ground.

10. A lifting jack including members slidably mounted relative to each other, one of said members having a head, and means associated with the head in position to engage an object to be lifted slightly in advance of the engagement thereof by the head for allowing the jack to be extended between the object to be lifted and the floor or ground.

11. A jack of the character described including members movable relative to each other for lengthening action, and means associated with said members for normally preventing an extending movement of said members and to be released by the object to be lifted when the jack is in lifting position to allow at least one of said members to drop downward.

12. A jack of the character described including members slidably connected together, and means for normally preventing relative extending action of said members, said members being extended upon the release of said means by the object to be lifted.

13. A jack of the character described including members slidably connected together, a catch for normally holding said members against relative extending action, and means for immediately releasing said catch when the jack is in position to engage a load to allow at least one of said members to drop downward to approximately close up the space between the object to be lifted and the floor or ground.

14. A jack of the character described including members slidably connected together, a trigger connected with one member and in a position to contact with the object to be lifted in advance of the jack, whereby to cause a release of the members of the jack to permit the lower member to immediately extend to the supporting surface below.

In testimony whereof I affix my signature.

JOHN ALBERT CHEAPE.
